COOLING OF BLADES IN MACHINES WHERE BLADING IS EMPLOYED

Georges Boulet, Toulouse, France

Application February 15, 1950, Serial No. 144,229

Claims priority, application France February 15, 1949

3 Claims. (Cl. 253—39.15)

My invention relates to machines provided with sets of blades, whether carried by a stationary or a moving part of the machine, in particular to turbines, compressors, and more particularly to machines having internally cooled hollow blades.

An object of my invention is to provide for an efficient cooling of the blades.

Another object is to provide for an efficient and well ruled circulation of cooling fluid through the various blades.

A further object in the case of multistage machines is to transfer heat from a stage to another by means of an inner fluid circulation through the blades from the most heated stage to the less one. Once this object attained, a still further object is then to provide multistage machines adapted to operate nearly isothermally, and in particular a nearly isothermic multistage compressor.

Still another object is to provide machines having at least one blade wheel, the blades of which are cooled by an inner circulation of cooling fluid, and therefore blade wheels or barrels carrying blades cooled as just said and which will be light, easy to machine and assemble, fluidtight and reliable in operation.

With these and other objects in view as will appear from the description given hereinafter of various embodiments of my invention, the latter consists in the provision and combination of means, and arrangement of parts, as will appear from said description and be more fully pointed out in the claims.

In the annexed drawings:

Fig. 1 is a section, through the axis, of a three-stage turbine of which the stationary and moving blades are cooled;

Figs. 2, 3 and 4 are respectively cross-sections carried out at various distances from the axis of rotation along the lines II—II, III—III, and IV—IV of Fig. 1;

Fig. 5 is a diagrammatic end-view of a cooling device for stationary blades;

Figs. 6 and 7 are respectively cross-sections along the lines VI—VI and VII—VII of Fig. 1;

Fig. 8 is an elevational diagrammatic view of a turbo-compressor with cooled blades; and

Fig. 9 is a view similar to Fig. 8 of a modified embodiment of cooling means for the blades of a turbo-compressor.

In the embodiment illustrated in Fig. 1 and that refers to a three-stage turbine, each of the stages is provided, in the usual way, with a plate 1 to the periphery of which are fastened the blades 2 that are hollow; each blade is fitted through its base with cross-section in the shape of a parallelogram (Fig. 2) over a teat of the same shape cut in the periphery of the plate 1, the base of the blade itself being imbedded in the grooves formed between two adjacent teats. The space between two adjacent plates is closed by a rippled wall 3, in the shape of a surface of revolution, fastened to these two plates;

2

as shown the distance of said wall to the axis of rotation of the turbine wheel decreases from the first stage, the blades of which are the most heated by the fluid flowing through the machine, to the other stages 5 the blades of which are less heated by said fluid. Outside this wall is an outer ring 4 with U-shaped cross-section with its opening directed towards the rotary axis of the turbine and that is also fastened to these adjacent plates 1. A closed chamber 5 is thus provided 10 between two adjacent plates; the adjoining chambers are in communication with each other through holes 6 going right through the plates in their central portion. A chamber 7 is arranged likewise on the outer surface of the end plates and is demarcated by an outer surface of the plate and rippled wall 8 covering this surface and fastened to the plate in question; this chamber 7 connects up also with the chambers 5 through holes 6 arranged in the central portion of the end plates. Radial tubes 9, 10 project into each blade 2 and are 20 arranged respectively with one near the leading edge of the blade and the other near the trailing edge. These two tubes emerge in the neighborhood of the blade end the farthest away from the rotary axis. They are fastened in the rim of the plate carrying the blade, a rim through which they go to emerge in the chambers 5 or 7. Furthermore, each plate 1 is provided in register with each blade with a radial passage 12 hollowed out in the body of the plate and that cuts one of the cross holes 6; it emerges on the other hand substantially in the centre of the fastening teat fitted on the base of the blade. It will be understood, under these conditions, that if there is in the chambers 5 and 7 and inside the hollowed blades a cooling fluid, the latter, as it is being heated through the passing of the propelling jet between the blades, will become heated more inside the blades than in the chambers 5 and 7 and that, as a consequence of the ensuing density variation, the denser fluid contained in the chambers 5 and 7 is centrifugalized through the tubes 9 and 10 while the warmer and less dense fluid is forced back by the previous one through the passages 12 and 6 and returns into the chambers 5 and 7. There is thus self-circulation inside the blades. It appears beneficial to make use of, as cooling fluid, a material possessing a vaporizing point that is less than the ordinary temperature of the propelling jet. There thus takes place a vaporization inside the blades while the chambers 5 and 7 enclose this material in the liquid or solid state. This material, for instance, may be formed, to advantage, by metallic salts as in standard practice.

On the other hand, since the different chambers 5 and 7 link up with each other, there occurs between them a more or less well-marked equalizing of the temperature so that the heat removed in the first blading set may be used to reheat the last lot of blading or several of the other blading sets and that there is thus automatic regeneration of power. It is therefore clear that the fluid within the chambers 5 and 7 is at a temperature less than that of the most heated blades 60 but greater than that of the blades of the less heated stage or last stage.

Fig. 1 shows besides the addition to the previous device of means intended to cool the fluid that circulates in closed circuit in the blades. For this purpose, in the chambers 5 located between two adjoining plates 1, there are arranged heat exchangers 14 formed in this case by annular flat chests with rippled wall carried by a central hollow hub 15. This hub is fitted directly on the adjoining plates 1 so as to form with them a continuous wall and the whole block of the plates and the hubs fitted on each other is held assembled to

gether through longitudinal stay-rods 16. The inside of the chest 14 is in communication through radial holes 17 and 18 with the inside of the hollow hub 15. A partition 19 inside the hub splits up the inner space of the latter into two divisions with no communication with each other and this partition 19 is fastened to a central tube 20 that is concentric with the rotary axis and fastened to the body of the plate 1 of the first stage. The inside of this tube is in communication, through holes 21, with the division 22 on the upflow side of the hub 16 while the other division 23 communicates freely round the tube 20 with the division 22 of the heat exchanger arranged in the adjacent chamber 5.

To the body of the plate of the last stage is fastened a tube 24 that is outside and concentric with the tube 20 with which it demarcates an annular passage 25 in communication with the division 22 of the heat exchanger arranged between the penultimate and the last stage. The tubes 20 and 24 are connected together, through the instrumentality of revolving joints 26, to a stationary outer collector 27 provided with a circular volute 28, communicating with the annular passage 25 and provided with an outlet pipe 29, and a central passage 30. The pipe 29 and the central passage 30 are connected through a pipe system, that is not shown, to means enabling a cooling fluid to be delivered through the central passage 30 into the tube 20 from where the fluid goes through the holes 21 into the head division 22 of the first exchanger 14, circulates inside the latter, leaves from it through the holes 18 into the division 23 from where it makes its way into the second exchanger and leaves from the latter through the annular area 25 between the tubes 20 and 24 and goes away, through the pipe 29 of the collector 27. Any suitable heat exchanger may be inserted in the outer pipe system.

The stationary blades 35 of the turbine shown in Fig. 1 are cooled likewise. For this purpose, they are hollow and are provided with an extension that goes through the outer wall 36 of the annular jacket where the propelling jet circulates and these extensions are immersed in a common cooling casing 37 that surrounds this jacket of which the outer wall forms preferably one of the walls of this casing; pipes 38 and 39 carried by this casing enable it to be connected through pipe systems, that are not shown, to means enabling a cooling fluid to be circulated therein, preferably in the same direction as that of the outflow of the propelling jet as shown by the arrows in Fig. 1. These stationary blades 35 are filled with metallic salts in a pasty form adapted to be vaporized at a temperature lower than that of the propelling jet.

A modification of the cooling of the stationary blades of a turbine is shown in Figs. 5 and 9. In this modification, there enter into each hollow blade two tubes 41, 42 headed towards the axis of the blading and that emerge inside the blade at two points that are at different distance from the axis. These two tubes 41, 42 are connected respectively to two different collectors 43, 44 of annular shape and that surround the blading. The collector 43 is connected to the tube emerging nearest to the rotary axis and is of lesser cross-section than the collector 44 into which converges the tube 42. The collectors 43 of the various bladings are connected up with a main pipe 45 while the collectors 44 are connected to a pipe 46. Means not shown drive back into the pipe 45 a cooling fluid, preferably of metallic salts in a liquid state, salts of sodium for example; this fluid is delivered, through the passage 45, to the various collectors 43 and, through the latter, to the tubes 41 of the different blades of each set of blading, then it leaves from these blades through the tubes 42 and is gathered together in the various collectors 44 from where it comes back through the general passage 46,

5 by means that ensure its circulation. There is therefore in this case forced circulation inside the vanes. This manner of carrying out the cooling of the stationary blades may be pointed out especially in the case of thin blades.

The various means as described for cooling the stationary blades and the moving blades of a turbine refer equally well to compressors, especially to axial compressors as shown in Figs. 8 and 9. In this case, however, in order to get as near as possible to isothermic compression, there is a separate casing 37a for the cooling of stationary vanes per compressor stage and these different casings are connected up in parallel on the distributors 50, 51 for the inlet and outlet of a cooling fluid of which the circulation is ensured by outer means connected to this distributor and that are not shown. Owing to this arrangement, the different compression stages may be kept substantially at the same temperature.

10 The same result may be secured in the case of cooling of the vanes through forced circulation and common feeding through a general passage as disclosed hereinabove for the turbine shown in Fig. 9.

15 Instead of feeding the various bladings or the various collectors through a distributor common to all the stages, each stage may be fed also through a separate pipe system or else sets of several stages and use may be made for each stage or each set of stages of a different volatile liquid suitable to the working temperature.

20 My invention, of course, is restricted in no way to the details of execution as shown or disclosed, which have been given only as an example. So it is that, without going outside the scope of the invention, the stationary vanes of a compressor or of a turbine may be cooled only or solely by the moving vanes.

25 In the case of machines provided with a multistage blading two or more stages of hollow blades may also be serially connected in order that a circulation may be provided within the hollow blades from the more heated stage to a less heated one.

30 What I claim is:

1. In a bladed fluid flow machine required to run at high temperature comprising a rotary wheel, blades carried by the latter, at least some of which are each internally provided with a cavity enclosing a cooling material of a nature such that it is within said cavity in a fluid state at the normal running temperature of the rotary wheel, and heat exchanging means carried by said wheel and in operative cooling relation with said cooling material to cool the latter, said heat exchanging means including a fluid tight chamber, and for each cooled blade at least two ducts both communicating at one of their ends with said chamber and at their other ends with the cavity of a blade, the emerging points of one of said ducts in the associated blade cavity and in said chamber being respectively further remote from the wheel axis than the corresponding emerging points of the other duct in said blade cavity and in said chamber.

2. In a machine as in claim 1, wherein further said wheel blading comprises a plurality of cooled blade stages, said cooled blades of at least two different stages having their respective ducts emerging in one and the same fluid tight chamber.

3. In a bladed fluid flow machine required to run at high temperature comprising a rotary wheel, blades carried by the latter, at least some of which are each internally provided with a cavity enclosing a cooling material of a nature such that it is within said cavity in a fluid state at the normal running temperature of the rotary wheel, and heat exchanging means carried by said wheel and in operative cooling relation with said cooling material to cool the latter, said heat exchanging means including a fluid tight chamber in communication with said blade cavities and containing said cooling material, said rotary wheel comprising a plurality

of cooled blade stages, the cooled blades of at least two different stages having their respective cavities in communication with the same chamber.
